UNITED STATES PATENT OFFICE.

HENRY DENNIS, OF ST. LOUIS, MISSOURI.

FLYING-MACHINE.

1,114,868.

Specification of Letters Patent. Patented Oct. 27, 1914.

Application filed September 9, 1913. Serial No. 788,944.

To all whom it may concern:

Be it known that I, HENRY DENNIS, a citizen of the United States, residing at St. Louis, in the State of Missouri, have invented certain new and useful Improvements in Flying-Machines, of which the following is a specification, reference being had therein to the accompanying drawing.

This invention relates to flying machines, and the principal object of the invention is to provide a machine having an improved wing construction which is so constructed that the upper and lower wings will be simultaneously raised and lowered, and also to provide pivotally mounted planes in the wings which are operated simultaneously with the vertical movement of the wings to permit an air current to pass through the wings when the wings travel upwardly, but to prevent the air current from passing through the wings when the wings travel downwardly.

Another object of the invention is to provide an improved means for moving the upper wings and for causing the lower wings to move with the upper wings.

Another object of the invention is to provide an improved means for rocking the pivotally mounted planes when the wings are moving.

Another object of the invention is to provide an improved type of frame for the flying machine.

With these and other objects in view this invention consists of certain novel combinations, constructions, and arrangements of parts as will be hereinafter fully described and claimed.

In the accompanying drawings:—Figure 1 is a front elevation of the flying machine. Fig. 2 is a side elevation of the machine. Fig. 3 is a top plan view of the machine with the canopy removed. Fig. 4 is a vertical longitudinal sectional view through the machine. Fig. 5 is a vertical transverse sectional view through the machine along the line 5—5, in Fig. 2. Fig. 6 is a fragmentary sectional view showing the manner of pivotally connecting the planes with the wings. Fig. 7 is a fragmentary sectional view of the bearing showing the manner of connecting the drive shaft with the rod operating the wings. Fig. 8 is a perspective view of the block which is mounted upon the shaft which operates the wings.

Referring to the accompanying drawings

it will be seen that this invention comprises a platform 10 which is supported by the wheels 11 and which carries the standards 12 which support the upper platform 13 provided with the railing 14. This platform 13 is braced by suitable braces 15, and the standards 12 are braced by bars 16 which connect the standards and thus greatly strengthen them.

The lower wings 17 are pivotally connected with the hinge ears 18 extending from the platform 13 and are provided with transversely extending planes 19 pivotally mounted by means of bolts 20 passing through the side bars of the wings 17. These wings 17 are substantially straight throughout their length and terminate in downwardly extending tapered end portions 21 which permit the wings to be raised easily and to cause them to take a better grip upon the atmosphere when pushed downwardly. The upper wings 22 which are curved throughout their length are pivotally connected near their inner ends with the arms 23 at the upper ends of the standards 24 mounted adjacent the forward and rear ends of the platform 13. These upper wings 23 are also provided with transversely extending planes 25 pivotally mounted by means of the pins 26 similar to the planes 19. It should be noted that since the upper wings are curved as clearly shown in Figs. 1 and 5 that the upper wings will obtain a very firm grip upon the atmosphere, thus permitting the machine to be quickly lifted from the ground when the wings are operated by the mechanism to be hereinafter described. A canopy 27 extends longitudinally above the center of the frame and is supported by the standards 28 having their lower ends connected with the blocks 29 secured to the standards 24.

Blocks 30 are slidably mounted in the standards 24 and are connected by the shaft 31 which passes through the slots 32 formed in the inner end portions of the upper wings 22. It will thus be seen that when the blocks 30 are moved vertically that the wings 22 will be rocked upon their pivots 33 and, thus cause the machine to be raised from the ground. Rods 34 connect the wings 22 with the lower wings 17 and it will thus be evident that when the upper wings are moved that the lower wings will be simultaneously moved in the same direction although as indicated by the dotted

lines in Fig. 5 these wings 17 will move in a different arc from the wings 22. Rods 35 are pivotally connected with the rail 14 at their inner ends and with the inner edge 5 portions of the planes 25 at their outer ends. Links 36 are connected with the rods 35 intermediate the length of the rods and have their lower ends connected with the inner edge portions of the planes 19 as clearly 10 shown in Fig. 5. From an inspection of this figure it will be seen that when the wings are raised to the position indicated in dotted lines that the planes will be tilted to the positions indicated, thus permitting the 15 air to pass through the wings and thus prevent the upward movement of the wings from causing the machine to have a tendency to move downwardly through the air.

A crank shaft 37 is rotatably mounted in 20 the lower portions of the standards 24 and is supported intermediate its length by the bearings 38. Links 39 connect the crank shaft with the pins 40 passing through the lower portions of the blocks 30 and it will, 25 therefore, be seen that when the crank shaft is rotated by the sprocket chains 41 which pass around the sprocket wheels 42 and around the sprocket wheels 43 mounted on the shafts of the motors 44 that the blocks 30 30 will be reciprocated vertically and through the standards 24 and thus the wings caused to move as already described. The propeller 45 is mounted upon the shaft 46 and carries a gear 47 meshing with a gear 48 35 mounted upon one end of the shaft crank shaft 37. This propeller will, therefore, be rotated when the engines 44 are started and will drive the machine forwardly.

The usual rear rudder 49 and forward 40 rudder 50 are provided together with suitable controlling means such as a handle 51 for the rear rudder and the bell crank lever 52 and link 53 for the forward rudder.

A switch box 54 is provided for controlling 45 the motors 44 and battery boxes 55 are provided for holding the batteries which supply the current to the motors 44.

When operating this machine the motors 50 are started by moving the lever 56 on the switch box and the wings and propeller blade will be caused to move through the mechanism described. These wings have a flapping motion somewhat similar to that of the wings of a bird and it will, therefore, 55 be possible to raise the machine in a comparatively small open space. The machine may be guided while in the air by the rudders and when it is desired to return to the earth the lever 56 may be moved to decrease the speed of the motors and the ma- 60

chine will be then gradually lowered until it reaches the earth.

Having thus described the invention what is claimed as new, is:—

1. A flying machine comprising a frame, 65 lower wings pivotally connected with said frame, standards carried by said frame, upper wings pivotally connected with said standards, planes pivotally mounted in said upper and lower wings, rods pivotally connected with said frame and with the planes of said upper wings, links pivotally connecting said rods with the planes of said lower wings, rods connecting said upper wings with said lower wings for causing 70 said lower wings to be moved simultaneously with said upper wings, and means for rocking said upper wings.

2. A flying machine comprising a frame having upper wings, lower wings, pivotally 80 mounted upper wings, planes pivotally mounted in said wings, rods connecting the planes of said upper wings with said frame, links connecting the rods with the planes of said lower wings, rods connecting said 85 upper and lower wings, and operating means for moving said upper wings.

3. A flying machine comprising a frame, upper wings pivotally secured to said frame, lower wings pivotally secured to said frame, 90 means secured to said wings for swinging the same simultaneously, planes carried by said wings, and means extending from said frame and engaging said planes whereby said planes will be automatically swung as 95 said wings are moved.

4. A flying machine comprising a frame, upper wings pivotally secured to said frame, lower wings pivotally secured to said frame, 100 a rod connecting said wings together, means for moving said upper wings whereby said lower wings will be moved simultaneously, planes carried by said wings, a rod extending from each side of said frame and engaging the plane of each upper wing, links connected to the central portions of said rods and engaging the rear portions of the planes of the lower wings whereby when said wings are shifted said rods and links will automatically shift said planes for allowing the 105 passage of air currents therethrough or will swing said planes to a closed position as the wings move downwardly.

In testimony whereof I hereunto affix my signature in presence of two witnesses.

HENRY DENNIS.
